Des. 225,300
Patented Dec. 5, 1972

225,300

HAND DRILL

Melvin H. Boldt, Glenview, Ill., assignor to G. W. Murphy Industries, Inc., Houston, Tex.

Filed Nov. 16, 1970, Ser. No. 25,991

Term of patent 14 years

Int. Cl. D8—01

U.S. Cl. D8—68

Fig.-1

Fig.-2

*Fig-3**Fig-4**Fig-5**Fig-6*FIG. 1 is a perspective view of a hand drill, showing my new design;

FIG. 2 is a right side elevational view of the hand drill illustrated in FIG. 1;

FIG. 3 is a top plan view of the hand drill illustrated in FIG. 1;

FIG. 4 is a bottom plan view of the hand drill illustrated in FIG. 1;

FIG. 5 is a rear elevational view of the hand drill illustrated in FIG. 1; and

FIG. 6 is a front elevational view of the hand drill illustrated in FIG. 1.

The broken line showing of a chuck is for illustrative purposes only.

I claim:

The ornamental design for a hand drill, as shown and described.
